INDUSTRIAL FORK LIFT TRUCK

Cecil Goodacre, Basingstoke, England, assignor to Lansing Bagnall Limited, Hampshire, England

Filed Nov. 3, 1970, Ser. No. 25,798

Term of patent 14 years

Int. Cl. D12—09

U.S. Cl. D14—3

FIG. 1 is a perspective view from the front and one side of the industrial fork lift truck showing my new design;

FIG. 2 is a perspective view from the front and the other side thereof;

FIG. 3 is a perspective view from the rear and the other side thereof;

FIG. 4 is a perspective view from the rear and said one side thereof.

I claim:

The ornamental design for an industrial fork lift truck, substantially as shown.
